Attn:

UNITED STATES PATENT OFFICE.

ROGER M. NEWBOLD, OF CHICAGO, ILLINOIS, ASSIGNOR TO THE ADAMS & WESTLAKE COMPANY, OF CHICAGO, ILLINOIS, A CORPORATION OF ILLINOIS.

DESIGN FOR A LAMP.

46,264.

Specification for Design.

Patented Aug. 11, 1914.

Application filed May 17, 1913. Serial No. 768,349. Term of patent 14 years.

To all whom it may concern:

Be it known that I, ROGER M. NEWBOLD, a citizen of the United States, residing at Chicago, county of Cook, and State of Illinois, have invented a new, original, and ornamental Design for Lamps, as illustrated in the accompanying drawing, forming a part thereof, and in which—

Figure 1 is a side elevation of the lamp; and Fig. 2 is a front elevation thereof.

I claim:

The ornamental design for a lamp, as shown.

ROGER M. NEWBOLD.
